CLARENCE T. EVANS, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTROMAGNETIC BLOW-OUT DEVICE.

1,313,176.

Specification of Letters Patent. Patented Aug. 12, 1919.

Application filed November 23, 1916. Serial No. 132,846.

To all whom it may concern:

Be it known that I, CLARENCE T. EVANS, a citizen of the United States, residing at Milwaukee, in the county of Milwaukee, and State of Wisconsin, have invented new and useful Improvements in Electromagnetic Blow-Out Devices, of which the following is a full, clear, concise, and exact description, reference being had to the accompanying drawing, forming a part of this specification.

This invention relates to electromagnetic blowout devices for electric switches and more particularly to a method of and means for centering between the pole pieces of the blowout device the arcs drawn by the switch contacts.

Electromagnet blowout devices for electric switches are preferably designed to repel the arc drawn between the switch contacts away from the winding of the blowout device and to direct the arc upwardly between the pole pieces of the blowout device for interruption. However, much difficulty has been experienced with this type of blowout device due to the tendency thereof to deflect the arc against one of the pole pieces, which quite frequently results in quick destruction of the insulating chute commonly provided between the pole pieces and the arc. It has been proposed to insure against such deflection of the arc by providing a tortuous magnetic circuit for the blowout device relative to the arc but so far as applicant is aware this has not proven a satisfactory solution of the problem.

According to the present invention it is proposed to insure centering of the arc by concentration of the magnetic flux of the blowout device in a relation to the arc such as to reverse the normal curvature of the magnetic lines of force which would otherwise deflect the arc toward one of the pole pieces, such concentration being preferably effected contiguous to the source of the arc. This method may be readily carried out in practice and the accompanying drawing shows certain embodiments of the invention which have given very satisfactory results.

50 In the drawing,

Figure 1 is a perspective view of a blowout device and a pair of arcing contacts, one side of the blowout device being broken away to disclose the contacts.

Figs. 2 and 3 are respectively a front elevational and top plan view of Fig. 1;

Fig. 4 is a side elevational view of a modified form of blowout device and associated contacts; and,

Fig. 5 is a front elevational view of Fig. 4.

Referring to Figs. 1 to 3, the blowout device comprises an electromagnetic winding 1 having magnetic pole pieces 2 and 3, insulating pole shields 4 and 5 and a transverse insulating barrier 6, said shields and barrier forming the usual insulating chute. Contacts 7 and 8 are arranged between the pole pieces and within the insulating chute in the usual relation but are of special construction. Whereas contacts are ordinarily formed of non-magnetic material, commonly copper, these contacts, the bulk of which may be of copper, or other desired material, are respectively provided with magnetic inserts 9 and 10. It is to be understood, however, that the contacts might be constructed solely of magnetic material, if preferred. In shape, the contacts are of a type commonly employed for an upwardly directed arc and as will be understood the arc travels up the faces of these contacts with a tendency to extend rearwardly of the contact 7 and forwardly from the contact 8.

For the moment disregarding the metal inserts in the contacts, and assuming polarity of the winding 1, such as would effect repulsion of the arc, the magnetic lines of force between the pole pieces would tend to bow to subject the arc in part to repelling lines of force concave with respect to said arc and in part to repelling lines of force convex with respect to said arc. Thus while the arc drawn between the contacts would always be repelled at right angles to the magnetic lines of force, that portion thereof subjected to repelling lines of force convex with respect thereto would tend to shift toward one or the other of the pole pieces. On the other hand, with the contacts provided with magnetic inserts as described, it will be observed that said inserts will concentrate the magnetic flux between the pole pieces adjacent to the source of the arc and will moreover so concentrate the flux that the maximum density of the flux in the region of the arc will be obtained midway between the pole pieces. In consequence,

the magnetic lines of force at the source of the arc will tend to bow as indicated in dotted lines, Figs. 2 and 3, said figures respectively representing the magnetic lines of force in a vertical plane and a horizontal plane substantially through the contacts. That is to say, the described concentration of the magnetic flux serves to reverse the curvature of the arc repellent lines of force extending between the pole pieces adjacent the contacts, thus rendering said lines of force concave rather than convex with respect to the point of arcing, such concavity continuing substantially throughout the length of the arc when formed, which relation insures centering of the arc within the chute in the manner previously described. It is, of course, to be understood that the centering of the arc becomes less important as the arc becomes attenuated and it has been found that if the arc be held to a centered course during a substantial degree of travel thereof it will inherently tend to hold to the same course throughout its travel. Accordingly it is not essential to insure the above described curvature of the magnetic lines of force throughout the entire range of the arc.

Referring now to Figs. 4 and 5, the same show contacts 11 and 12 of usual construction, that is, of non-magnetic material, and specially constructed pole pieces 18 and 14 to effect concentration of the magnetic flux adjacent to the source of the arc similar to that described. In this instance the pole pieces are respectively cut away contiguous to the contacts on corresponding lines 15 and 16. As so formed the pole pieces are hook shaped and provide for concentration of the magnetic flux along the line of an arc or arch over the contacts with the result that the magnetic lines of force throughout the extent of such arch will tend to curve toward the contact 12, as illustrated in dotted lines, Fig. 5, or in other words, substantially as in Figs. 2 and 3 with the same result.

What I claim as new and desire to secure by Letters Patent is:

50. 1. The method of centering an arc between the pole pieces of an electromagnetic blowout device, wherein the magnetic flux traverses a single loop path with respect to the arc and in a direction to repel the arc from the winding of said device, consisting in concentrating the magnetic flux of the device in a relation to the arc to reverse the curvature of the magnetic lines of force of the device which would otherwise divert the arc from centered relation with the pole pieces.

60. 2. The method of centering an arc between the pole pieces of an electromagnetic blowout device, consisting in so concentrating the magnetic flux of the device that the

density thereof in the region of the arc is greatest midway between the pole pieces of the device.

3. The method of centering an arc between the pole pieces of an electromagnetic device consisting in concentrating the magnetic flux of the device adjacent to the source of the arc and in such a manner that the density of the magnetic flux in the region of the arc is greatest midway between the pole pieces of the device.

4. The method of centering an arc between the pole pieces of an electromagnetic blowout device, wherein the magnetic flux tends to repel the arc from the winding of the device, consisting in concentrating the magnetic flux of the device contiguous to the source of the arc whereby the magnetic lines of force of the device determining the path of the arc between the pole pieces during a substantial degree of its travel normally tend to curve in the same direction as the repelling magnetic lines of force of the arc.

5. The combination with contacts adapted to draw an arc therebetween, of an electromagnetic blowout device including a winding and pole pieces for said winding disposed on opposite sides of said contacts, said winding creating a magnetic flux to repel therefrom the arc drawn between said contacts and certain of said elements being constructed to concentrate the magnetic flux of said device in a relation to the arc to reverse the curvature of the magnetic lines of force of said device which would otherwise effect shifting of the arc laterally and to thereby insure centering of the arc between said pole pieces.

6. The combination with contacts adapted to draw an arc therebetween, of an electromagnetic blowout device including a winding and pole pieces for said winding disposed on opposite sides of said contacts, said winding creating a magnetic flux to repel therefrom the arc drawn between said contacts and certain of said elements being constructed to concentrate the magnetic flux of said device contiguous to the source of the arc to thereby insure normal curvature of the magnetic lines of force of said device contiguous to the source of the arc substantially parallel to the repelling magnetic lines of force of the arc.

7. The combination with contacts adapted to draw an arc therebetween, one of said contacts including a magnetic part, of an electromagnetic blowout device including an electromagnetic winding and pole pieces for said winding disposed on opposite sides of said contacts, said contact including said magnetic part providing for concentration of the magnetic flux between said pole pieces and thereby tending to effect curvature of such magnetic lines of force of said device.

acting to repel the arc as to insure centering of the arc between the pole pieces.

8. The combination with contacts adapted to draw an arc therebetween, each having a 5 magnetic part, of an electromagnetic blow-out device including a winding and pole pieces therefor disposed on opposite sides of said contacts, the magnetic parts of said contacts providing for concentration of the 10 magnetic flux between the pole pieces and thereby tending to effect curvature of magnetic lines of force of said device acting to repel the arc such as to insure centering of the arc between the pole pieces.
- 15 9. The combination with contacts adapted to draw an arc therebetween, of an electromagnetic blowout device including a winding and pole pieces for said winding disposed on opposite sides of said contacts, said 20 winding creating a magnetic flux to repel therefrom the arc drawn between said con-

tacts and certain of said elements providing for concentration of the magnetic flux of the device so that the density thereof in the region of the arc is greatest midway between 25 said pole pieces.

10. The combination with contacts adapted to draw an arc therebetween, of an electromagnetic blowout device including a winding and pole pieces for said winding 30 disposed on opposite sides of said contacts, said winding creating a magnetic flux to repel therefrom the arc drawn between said contacts and certain of said elements providing for concentration of the magnetic 35 flux of said device adjacent to the source of the arc in such a manner that the density of the magnetic flux in the region of the arc is greatest midway between said pole pieces.

In witness whereof I have hereunto subscribed my name.

CLARENCE T. EVANS.
